JAMES J. CURTIS, OF CHICAGO, ILLINOIS.

WHISTLE.

1,283,683.

Specification of Letters Patent.

Patented Nov. 5, 1918.

Application filed February 25, 1918. Serial No. 218,980.

To all whom it may concern:

Be it known that I, JAMES J. CURTIS, a citizen of the United States, residing at Chicago, in the county of Cook and State 5 of Illinois, have invented certain new and useful Improvements in Whistles, of which the following is a specification.

This invention relates to improvements in whistles of a type which are particularly 10 designed for use by traffic controlling policemen in giving signals, but which may be used by others and for other purposes, and it consists in certain peculiarities of the construction, novel arrangement and operation 15 of the various parts thereof as will be hereinafter more fully set forth and specifically claimed.

The principal object of the invention, is, 20 to provide a manually operated whistle which shall be simple and inexpensive in construction, compact in form, strong, durable, efficient in operation and sufficiently powerful to produce very loud and shrill sounds or blasts. Another object of the invention 25 is to furnish a whistle of the above mentioned general character which can be operated by the use of one hand only, and in such a manner that the shrill blasts or sounds produced thereby can be made in 30 quick succession or repeatedly, and the length thereof regulated as desired. Other objects and advantages of the invention will be disclosed in the subjoined description and explanation.

35 In the accompanying drawing which serves to illustrate an embodiment of the invention—

Figure 1 is a vertical sectional view 40 through the body or cylinder of the whistle showing the lower extremity thereof, the rotary fan and operating handle in elevation and illustrating the parts in their normal positions.

Fig. 2 is a vertical sectional view taken 45 on line 2, 2 of Fig. 1 looking in the direction indicated by the arrows, and

Fig. 3 is a cross sectional view taken on line 3, 3 of Fig. 1 looking in the direction indicated by the arrows.

50 Like numerals of reference refer to corresponding parts throughout the different views of the drawing.

The reference numeral 10 designates as 55 a whole the cylinder or body of the whistle, which may be made of any suitable size, form and material, but by preference cylin-

drical in shape as shown, and of sheet metal. The body or cylinder 10 is herein shown as being made of two pieces 11 and 12 which are mainly semi-circular in cross section 60 as will be clearly understood by reference to Fig. 3 of the drawings. One of said sections, say the section 11, is provided at each of its edges with an outwardly located angular guide 13 while the other section 12 65 is provided at each of its edges with an angular guide 14 which latter guides embrace the guides 13 and can be soldered or otherwise tightly secured thereto. As is clearly shown in Figs. 1, 2 and 3 of the 70 drawings, one of the guides 13 is provided on its wall adjacent to the portion 11 with a rack-bar 15 which may be produced by transversely corrugating said wall. As shown the lower portions of the sections 11 75 and 12 constituting the cylinder 10 are contracted and form a tubular neck or nozzle 16, the lower end of which is closed. Above its closed end the nozzle or neck 16 is provided with an outwardly flared opening 17 80 and located in the nozzle or neck 16 is a block 18 which is inclined on its upper surface toward the opening 17 as is clearly shown in Fig. 2 of the drawing, in which view it will be observed that a narrow space 85 or opening 19 between the block 18 and the wall of the nozzle 16 in which the opening 17 is formed is left or provided for the passage of air from the cylinder when the whistling noise is produced. The upper end 90 of the cylinder 10 is internally screw threaded as at 20 to receive a screw threaded cap 21 which has in its central portion a pair of openings 22 which are separated by a bar 23, see Fig. 1 of the drawing. 95

Referring again to the guides 13 and 14 of the sections 11 and 12 of the cylinder, it will be understood that the wall 24 of the guide 14 opposite the wall of the guide 13 which is provided with the rack-bar 15 or 100 corrugations is located in parallelism with said rack-bar at a distance therefrom, in order that said walls will form a longitudinal guideway on one side of the cylinder for a pinion 25 mounted on one end of the shaft 105 26 of the rotary fan. The corresponding wall 24 of the guide 14 on the opposite side of the section 12 and the wall 15^a of the guide 13 on the opposite side of the section 11 form a guideway for a roller 27 which is 110 mounted on the opposite end of the shaft 26 from that on which the pinion 25 is mount-

ed. The shaft 26 is horizontally journaled in the downwardly projected prongs 28 of a yoke 29 which has an opening in its middle portion, in which is swiveled the lower end 5 of the operating rod 30 which rod is tubular in shape and divided longitudinally thus furnishing two prongs 31 which are extended through the openings 22 in the cap 21 or cover for the cylinder. Located in the 10 operating rod 30 is a spiral spring 32 which rests at its lower end against the bar 23 and at its upper end against a knob or button 33 which is detachably secured to the upper end of the operating rod. At diametrically 15 opposite points the cap 21 is provided with finger pieces 34 by means of which the body of the whistle may be held between the first and second fingers of the hand while the button or knob 33 on the operating rod will 20 rest against the palm of the hand. The fan shaft 26 is provided with a number of wings or vanes 35 which radiate therefrom and are of sufficient dimensions to fit closely to the walls of the body of the whistle yet so 25 as to rotate therein without undue friction.

From the foregoing and by reference to the drawing it will be understood and readily seen, that assuming the parts are in the 30 positions shown in Figs. 1 and 2 of the drawings and it is desired to produce a loud whistling sound or blast, all that is necessary is to force the yoke 29 carrying the rotary fan downwardly in the body 10 or toward its reduced end by applying pressure 35 to the knob or button 33 on the operating rod. As soon as pressure is removed from said button or knob it is obvious that the operating rod 30, the yoke 29 and rotary fan will be returned to their normal posi-

tions by the action of the spring 32 against 40 said knob or button.

Having thus fully described the invention, what I claim as new and desire to secure by Letters Patent is—

1. In a device of the character described, 45 the combination with a hollow body having a nozzle at one of its ends provided with an opening, of a block located in said nozzle and partially closing the same between said opening and said body, a rotary shaft transversely mounted in the body for movement longitudinally with respect to the same, radial vanes on said shaft, and means to reciprocate the shaft.

2. In a device of the character described, 55 the combination with a hollow cylindrical body having one of its ends tapered and provided with an opening in its wall, of a block located in said tapered portion and partially closing the same between said opening and the body, said body having diametrically disposed longitudinal guideways, 60 a rack on one of the walls of one of said guideways, a yoke located between the guideways, a shaft journaled on the yoke and extended into the guideways, a pinion on the shaft to engage the said rack, radial vanes on the shaft, an apertured cap on the larger end of the body, a rod extended from the yoke through said cap, a knob on the free 70 end of said rod and a spring interposed between said knob and cap to actuate the yoke in one direction.

JAMES J. CURTIS.
